CLAIM

The ornamental design for a digital recorder, as shown and described.

DESCRIPTION

FIG. 1 is a first perspective view of a digital recorder according to the present invention.

FIG. 2 is a second perspective view of the digital recorder of FIG. 1.

FIG. 3 is a front view of the digital recorder of FIG. 1.

FIG. 4 is a back view of the digital recorder of FIG. 1.

FIG. 5 is a right side view of the digital recorder of FIG. 1.

FIG. 6 is a left side view of the digital recorder of FIG. 1.

FIG. 7 is a top view of the digital recorder of FIG. 1; and,

FIG. 8 is a bottom view of the digital recorder of FIG. 1.

1 Claim, 7 Drawing Sheets

FIG. 1

FIG. 2

FIG. 3

FIG. 4

FIG. 5

FIG. 6

FIG. 7

FIG. 8
